14 Claims. (Cl. 138—17)

This invention relates to presses and is illustrated as embodied in a press of the hydraulic type designed for use in smooth plating, embossing and other pressure applying operations upon 5 hides, skins, leather and other similar pieces of work. It is to be understood, however, that the invention and various important features thereof may have other applications and uses.

In a well-known type of hydraulic press, one 10 of the presser members is moved toward the other to effect pressure applying operations by means of a hydraulically operated piston which is operated by an auxiliary piston designed to serve also as a valve mechanism for controlling the application 15 of a pressure medium under pressure to the first-mentioned piston. It is a disadvantage of such prior constructions that little, if any, variation in the thickness of the work or in the resistance encountered by the auxiliary piston before 20 the application of pressure to the main piston is permissible, since if the resistance be too great the auxiliary piston cannot move sufficiently to initiate the application of pressure directly to the main piston. Even if the work be compressible to 25 such degree as to permit movement of the auxiliary piston to the point of initiating the application of pressure directly to the main piston, such movement of the auxiliary piston may be so slow as to render the press valueless from the stand- 30 point of productive capacity.

It is an object of this invention to provide an improved press of the type described whereby the productive capacity of the press may be substantially greater than heretofore, since work 35 varying considerably in thickness or in the resistance offered to the movement of the pistons may be acted upon in the improved press without appreciably slowing up the speed of the press.

To these ends and in accordance with an im- 40 portant feature of the invention a piston supporting the movable platen of a press is arranged to be moved by an auxiliary piston constructed and arranged to travel upwardly always the same predetermined distance, with respect to the cylinders enclosing the pistons, before the pressure medium is applied under pressure directly to the first-mentioned piston. By this arrangement 45 movement of the movable platen to close the gap between the fixed platen and the movable platen 50 with the work thereon is accomplished in minimum time, a lost-motion connection between the pistons being provided to accommodate variations in the thickness of the work. As illustrated 55 between the pistons, the tension of the spring

means being such as to support and cause movement of the main piston and of the platen associated therewith until such platen and piston meet with substantial resistance from the work. When the platen moved by the piston commences to encounter substantial resistance from the work the spring means begins to yield, permitting the auxiliary piston to continue its movement to effect control of the application of hydraulic pressure directly to the first-mentioned or main piston.

It is a further important feature of the invention that the main piston is mechanically connected to operate a valve to open position to permit of the escape of the pressure medium back of the main piston so that the latter may return to initial position following a pressure applying operation. Advantageously, this valve mechanically operated from the main piston is embodied in an organization wherein only one passageway is provided for carrying the pressure medium to 75 and away from the cylinder associated with the main piston.

In an illustrated embodiment of the invention, an important feature of the invention resides in the provision of a port and passageway in the internal walls of the cylinders to afford communication between the cylinders under control of the auxiliary piston. This arrangement is simple and durable and efficient for the purpose intended, since it reduces the number of pipes and pipe openings into the cylinders and minimizes the possibility of leakage from the cylinders during applications of pressure upon the work.

These and other features of the invention and novel combinations of parts will now be described in detail and then pointed out in the appended claims.

In the drawings,

Fig. 1 is a front view, partly in section, showing important features of a press illustrating one embodiment of the invention;

Fig. 2 is a side elevation of the press shown in Fig. 1, certain parts being in section taken along the line II—II of Fig. 1;

Fig. 3 is a plan view from below, and partly in section, of means for operating one of the valves from the lower platen of the press;

Fig. 4 is a plan view from above and partly in section showing certain valves and a manually operable member by means of which the operator secures control of the press;

Fig. 5 is a view in front elevation of a press of simplified construction which also embodies important features of the invention;

Fig. 6 is a view in side elevation of the press

shown in Fig. 5, part of the liquid supplying means being omitted in order to show other parts more clearly; and

Fig. 7 is a horizontal, sectional view through the main piston cylinder of the press of Fig. 5 and through the manually operable valve by which the operator secures control of the press.

In the press illustrated in Figs. 1 to 4, inclusive, which is designed particularly for smooth plating and embossing operations upon hides, skins, leather and other similar pieces of work, there is provided an upper platen 2 carried fixedly by a downwardly facing portion of a C-shaped frame 4, the platen 2 being arranged to be heated in a well-known manner by steam pipes 6 and 8 (Fig. 1). For co-operation with the upper platen 2 there is provided a lower platen 10 arranged to be carried by a piston 12, a movable connection being provided between the platen 10 and the piston 12 by means of a boss 14 on the platen 10 having a spherical surface resting upon a complementally curved spherical surface formed as a socket 16 in the upper end of the piston 12. The purpose of the movable connection between the platen 10 and the piston 12 is to permit adjustment between the platen 10 and the platen 2 so that these platens will accommodate self-adjustingly pieces of work wherein a substantial portion of the work differs from other portions of the same piece of work in thickness dimensions. As shown, the piston 12 is movable vertically in a piston cylinder 18, and, by preference, upwardly by pressure exerted by an auxiliary piston 20 (Fig. 2) concentrically arranged with respect to the large piston 12. As illustrated, the auxiliary piston 20 is movable vertically within a piston cylinder 22 which has a port 24 for the admission of a liquid medium under pressure. It will be readily understood that, upon admitting liquid medium under pressure through the port 24 the auxiliary piston 20 will be forced upwardly, thus lifting the piston 12 and with the latter the platen 10, so that a piece of work supported upon the upwardly facing work supporting surface of the platen 10 will be pressed against the downwardly facing surface of the platen 2.

In order to insure that the large piston 12 will be moved, throughout substantially its entire upward stroke, by the auxiliary piston 20, irrespective of the thickness of the work interposed between the two platens 10 and 2, there is provided in the illustrated construction a yielding or a lost motion connection between the two pistons 12 and 20. As shown, this yielding connection comprises a spring 26 arranged to surround a reduced portion 28 of the piston 20. In order to tension the spring 26 there is provided a plate 30 slidable upon the piston part 28, a nut 32 being screw threaded upon the end of the piston part 28 so that it may be adjusted to cause the plate 30 to exert the required pressure upon the spring 26. Preferably the nut 32 with the plate 30 will be adjusted to tension the spring 26 to such an extent that the spring will slightly more than support the piston 12 and the platen 10 without yielding. Hence, when the platen 10 starts to press the work against the platen 2 so that the piston 12 encounters the resistance of the work, the spring 26 is compressed due to the sliding connection between the two pistons, thus permitting the auxiliary piston 20 to move upwardly always to the same point, irrespective of the thickness of the work being operated upon. It is clear that the spring 26 is compressed when it meets a resistance predetermined by the ten-

sion of the spring secured through adjustment of the plate 30 and nut 32. This point to which the auxiliary piston 20 rises is determined by a port or ports 34 in the auxiliary piston 20, the port or ports 34 being at the upper end of a passageway or bore 36 axially located in the auxiliary piston and communicating at its lower end with the chamber within the piston cylinder 22. It will be clear that upon applying liquid medium under pressure to the lower end of the auxiliary piston 20 the latter will be forced upwardly, thus carrying the large piston 12 and the platen 10 into pressure applying relation with respect to a piece of work between the platens 10 and 2 and that the auxiliary piston 20 will continue to move upwardly until the port or ports 34 are in position to open into the chamber of the main piston cylinder 18. When this occurs the pressure in the cylinder 22 is instantly communicated to the liquid medium within the piston cylinder 18. Pressure is then gradually built up within the piston cylinders 18 and 22 whereby the required pressure on the work between the platens is obtained. It is to be noted, moreover, that the movement of the main piston 12 to a point where pressure on the work begins is accomplished by the auxiliary piston 20 irrespective of the thickness of the work, this arrangement insuring the desired speed in the upward movement of the piston 12, as will be pointed out more clearly hereinafter.

While the piston 12 is being moved upwardly by the auxiliary piston 20, a liquid medium is flowing into the piston cylinder 18 through a pipe 40 into which the liquid passes from a pipe 42, a valve 44 in valve box or casing 45 being free to move upwardly. Since the piston 12 during its upward movement within the cylinder 18 acts as a suction piston, liquid will be drawn from a reservoir (not shown) through the pipe 40 past the valve 44 which would thus be lifted by the entering liquid even if no other means were provided for lifting the valve. It follows that the space within the cylinder 18 below the piston 12 is completely occupied by liquid at the time that the port or ports 34 in the auxiliary piston 20 arrive in communicating relation with respect to the cylinder 18. Hence, further upward movement of the piston 12 during the building up of the pressure within the cylinders 18 and 22 and compression of the work is dependent upon a minimum amount of fluid passing from the cylinder 22 through the port or ports 34 to the cylinder 18. If a considerable amount of liquid under pressure had to pass through the restricted port or ports 34 into the cylinder 18 during upward movement of the pistons 12 and 20, this upward movement of the pistons would be considerably slower than in the construction shown. In other words, the necessary amount of liquid medium to apply pressure to the bottom surface of the piston 12 is practically all in the cylinder 18 at the time the port or ports 34 reach the cylinder 18 and hence no time is lost in introducing any substantial amount of liquid medium through the ports 34, it being understood that the valve 44 closes firmly at the instant the ports 34 reach communicating position with respect to the cylinder 18 and hence that no more liquid can enter the cylinder 18 through the pipes 40 and 42.

For conducting a liquid medium under pressure to the auxiliary piston cylinder 22 from a constantly running pump (not shown) there is provided a pipe 50 (Fig. 1) which discharges through a passageway 52 in a valve block 54

to a pipe 56 connected with a pipe fitting 58. Leading from the pipe fitting 58 is a pipe 60 (Fig. 2) which terminates at the port 24 in the auxiliary piston cylinder 22. Also leading from 5 the pipe fitting 58 is another pipe 62 which opens into a small chamber 64 (Fig. 2) in the valve block 45. A ball valve 66 closes a port leading from the chamber 64 to the pipe 40 when pressure from the pump is applied to the liquid in 10 the pipes 60 and 62. Hence, liquid will not escape from the cylinder 18 and from the pipe 40 past the ball valve 66 while pressure is being built up within the cylinder 18 since the same pressure is being built up within the chamber 64 15 as within the piston 18. When, however, pressure within the pipes 60 and 62 and within the auxiliary piston cylinder 22 is released, by means which will subsequently be described, the ball valve 66 will serve as a quick acting release for 20 the liquid under pressure in the piston cylinder 18 through the communicating pipe 40 so that the piston 12 may start its downward movement by discharging liquid past the ball valve 66, the course of this liquid being through pipe 62 (Fig. 25 1), pipe fitting 58, pipe 56, passageway 52, thence through a port 68 and a passageway 70 leading by the pipe 42 back to the tank or reservoir (not shown).

In order to facilitate discharge of the liquid 30 pressure medium from the piston cylinder 18 as the piston 12 moves downwardly, means is provided for lifting the valve 44 so that liquid may escape from the pipe 40 to the pipe 42 which leads to the tank or reservoir. Conveniently, the means just referred to is controlled 35 by connections with the platen 10 and comprises a rod serving as a valve stem 72 (Fig. 2) located below and in line with the axis of the valve 44, the rod or valve stem 72 being pivoted 40 at 74 (Figs. 1 and 3) to a crank arm 76 secured to a shaft 78 mounted in bearings furnished by brackets 80 and 82 secured to the frame 4 of the press. Also secured to the shaft 78 are links 84 and 86 (Figs. 1 and 3) pivoted 45 at their other ends to links 88 and 90 which at their upper ends are pivoted to ears 92 on the platen 10. It will be clear from an inspection of Figs. 1, 2 and 3 that as the platen 10 moves downwardly the shaft 78 will be rocked whereby 50 the rod or valve stem 72 will be lifted to unseat the valve 44, the valve 44 rising higher as the piston 12 descends and thus affording a gradually enlarged passageway, in addition to the pipe 62, for the liquid to pass from the cylinder 18 55 through the pipe 40 and 42 back to the reservoir or tank.

Means is provided for enabling the operator to initiate a pressure applying operation, the same means being conveniently operable to terminate a pressure applying operation. In the construction shown the means just referred to comprises a hand lever 93 (Fig. 1) movable about the axis of a vertical pin 95, the hand lever having a segmental gear 97 (Figs. 1 and 4) arranged 60 to be in mesh with a pinion 99 having screw threaded engagement with stem 101 of a valve 103. When the handle portion of lever 93 is drawn toward the front of the machine the valve 103 is moved toward the port 68 to close the latter, thereby forcing the liquid from the pump to pass along the passageway 52 and by way of the pipe 56 to the pipe coupling 58 from which the liquid under pressure is carried by pipe 60 to the auxiliary cylinder 22. In this way the 65 operator can initiate a pressure applying opera-

tion whenever he has a piece of work properly disposed upon the platen 10. In order to provide for escape of the liquid under pressure when the pressure rises above a certain predetermined amount, there is provided a spring pressed valve 105 (Fig. 1) the stem of which is movable in a valve cylinder 107 which encloses also a spring 109 which may be adjustably tensioned by a set screw 111 arranged to press upon a plate 113 resting upon one end of the spring 109. When the spring pressed valve yields upwardly, the pressure is relieved by fluid escaping through the passageway 70 and pipe 42 back to the tank or reservoir. While the liquid under pressure from the pump may be allowed to continue to build up pressure within the piston cylinders 18 and 22 until pressure is released by the yielding of the spring pressed valve 105, it is to be understood that the operator may terminate a pressure applying operation at any time simply by moving the hand lever 93 toward the back of the machine, that is, in a direction the reverse of that which secures initiation of a pressure applying operation. When the hand lever 93 is turned in the direction away from the front 100 of the press, the valve 103 is lifted away from the port 68 so that liquid from the pump coming in through the pipe 50 may pass through the port 68 to a passageway 70 which connects with the pipe 42 which leads directly back to the 105 tank or reservoir.

In operating the illustrated press, assuming that the platen 10 is in lowered work receiving position, the piece of work is introduced upon the upper face of the platen 10 and smoothed 110 out by hand or otherwise to remove any wrinkles or folds in the work. As soon as the work is properly conditioned for a pressing operation, the operator pulls the hand lever 93 toward the front of the machine, thus causing the valve 103 115 to close the port 68 whereby liquid under pressure is caused to pass from the pump to the auxiliary piston cylinder 22. Upward movement of the auxiliary piston 20 lifts the main piston 12 and presses the platen 10 with the work thereon 120 against the upper platen 2. No matter what the thickness of the work the piston 12 is caused to travel throughout substantially its complete upward stroke through pressure exerted by the auxiliary piston 20, work of different thicknesses 125 being properly taken care of through the yielding of the spring 26 interposed between the two pistons. Since the illustrated construction is specially designed for smooth plating and embossing operations on hides, skins and pieces 130 of leather, the range of thickness is relatively small. When the port or ports 34 in the auxiliary piston 20 arrive at communicating position with respect to the piston cylinder 18 pressure in the liquid pressure medium is transmitted 135 instantaneously from the auxiliary cylinder 22 to the piston cylinder 18 and pressure is gradually built up in the piston cylinder 18. Whatever slight upward movement of the piston 12 takes place in smooth plating or embossing operations 140 upon the work, involving a certain compression of the work, is caused by liquid under pressure passing through the port or ports 34 into the piston cylinder 18. Since, however, the piston 18 is substantially or nearly at the end of its upward stroke when the port or ports 34 reach communicating position with respect to the cylinder 18, there is provided an arrangement wherein the very minimum amount of liquid must pass 145 through the restricted port or ports 34. In other 150

words, practically all of the upward movements of the piston 18 has been caused directly by the auxiliary piston 20 in an expeditious manner. When the operator decides that the plating or 5 embossing operation has been satisfactorily performed, he terminates the operation by moving the handle lever 93 away from the front of the press. As before stated, this opens the port 68, thus allowing the liquid from the pump to escape 10 back to the tank or reservoir. As soon as the port 68 is opened pressure in the liquid in the auxiliary cylinder 22 instantly falls, this being true also of the pressure in the pipe 62 back of the ball valve 66 so that both pistons 15 may move downwardly displacing the liquid in their respective cylinders until the platen 10 has returned to its initial work receiving position. The work which has been operated upon is then removed and a fresh piece inserted as a preliminary 20 to repetition of the operations just described.

The press disclosed in Figs. 5, 6, and 7 of the drawings represents a simplification in certain respects of the press described in the foregoing 25 paragraphs. Nevertheless it possesses many of the important features and advantages of the press first described. This simplified press comprises an upper platen 102 carried fixedly by a heavy overhanging frame member 104 secured by bolts 106 to a lower frame member 108. For strengthening the upper curved frame member 104 and for resisting deflection of the frame member 104, there are provided two heavy bars for rigidly connecting the frame member 104 to 30 frame member 108, one of the bars being shown at 110 in Fig. 6.

For co-operating with the upper platen 102 there is provided a platen 112 having an upwardly facing work supporting surface, the platen 112 being mounted by a ball and socket joint 114, 116, in a piston 118. As shown, the piston 118 is supported in a cylinder 120 within which it is a fluid-tight fit.

For lifting the piston 118 there is provided an auxiliary piston 122 indicated in dotted lines in 45 Fig. 5 and shown in cross section in Fig. 7 of the drawings. This piston 122 is very much smaller than piston 118 and is fitted to slide within a small cylinder or bore 124. When a liquid 50 medium under pressure is admitted through a pipe 126 and through a port 127 into the lower end of the cylinder or bore 124, the auxiliary piston 122 is caused to move upwardly carrying with it the large piston 118. As shown most clearly 55 in Fig. 5 of the drawings, the pipe 126 is connected with a pump 128, a port 130 (Fig. 7) in the pipe 126 being provided at a point conveniently situated for control by the operator. When the port 130 is closed, as indicated in Fig. 5, and 60 as shown in Fig. 7, the liquid medium under pressure is caused to flow from the pump 128 to the cylinder or bore 124 of the auxiliary piston 122. To interrupt the application of pressure to the auxiliary piston 122 it is necessary only to 65 open the port 130 by turning a hand wheel 132 fastened to a valve pin 134 having a screw threaded engagement at 136 with a valve cap 138. Upon turning the hand wheel 132 in a counterclockwise direction in Figs. 5 and 7, a cone-shaped end 70 140 of the valve pin 134 is retracted so that the liquid medium under pressure in the pipe 126 may escape through the port 130 into the bore 140 of a pipe 142 by which the liquid medium is carried back to a reservoir 144.

75 As the piston 118 rises through pressure ex-

erted thereon by the auxiliary piston 122, liquid from the reservoir 144 flows through a pipe 146 into the lower part of the cylinder 120, the piston 118 acting as a suction piston to draw in liquid from the pipe 146 and reservoir 144. While 80 the piston 118 is in its lower or initial position and while it is rising toward pressure applying position with respect to the platen 102, a valve 148 (Fig. 5) is in lowered position so that a port 150 is open to permit of the passage of the liquid medium along the pipe 146 to the cylinder 120. As shown, the valve 148 is secured to the lower end of a valve stem 152 to which is fixedly attached a disk 154 movable in a chamber surrounding an intermediate portion of the valve stem 152, a spring 156 being provided which tends always to move the valve 148 to its port-closing position. However, the port 150 is open during practically all of the upward movement of the piston 118, the valve 148 at the lower end of the stem 152 being held downwardly away from the port 150 through means connected with the piston 118. This control of the valve 148 by the piston 118 is effected in the illustrated construction by a lever 160 pivoted at 162 between a pair of links 164 in turn pivoted at 166 to valve casing 168, the lever 160 having a shallow recess for the reception of the upper rounded end 169 of the valve stem 152. Conveniently the other end of the lever 160 is rounded and received as a ball 105 end in a socket formed in a member 170 secured to the piston 118 near the upper end thereof. Preferably, and as shown, the rounded end of the valve stem 152 is formed as a separate member 169 and is screw threaded on the stem 152 so as to be adjustable. When work of a substantially greater thickness than that last treated in the press is to be operated upon, the member 169 should be adjusted slightly in a downward direction on the valve stem 152 so as to open the port 150 correspondingly earlier. 110

As illustrated, means is provided for applying the liquid medium under high pressure directly to the lower end of the large piston 118. In order to accomplish this in a simple and efficient manner without the provision of a special valve, such as has commonly been provided in the past, the auxiliary lifting piston 122 is made to serve also as a valve piston. In order to accomplish this result one or more ports 172 (Figs. 5 and 7) are 115 provided in the internal wall of the auxiliary piston cylinder 124 by which the liquid medium under pressure may pass into the piston chamber 120 and thus act directly on the piston 118 at a predetermined point in the upward movement of the piston 122. As shown, the ports 172 are of substantially restricted area, being in the form of slots, the long dimension of each slot extending in the direction of the length of the auxiliary piston 122, and each slot providing a 120 passageway in the internal wall of the cylinder 124 to connect cylinder 124 with cylinder 120. Hence, as the auxiliary piston is approaching its uppermost position the lower portions of the ports 172 are gradually and progressively uncovered to admit the liquid pressure medium into the cylinder 120 from the cylinder 124. As 125 soon as these ports are opened the pressure in the high pressure medium in the pipe 126 and in the cylinder 124 is transmitted instantaneously to the liquid medium within the cylinder 120. Hence, the high pressure of the pump is transmitted directly to the piston 118. In order that this may be accomplished, the arrangement, including the position of the piston 118, is such 130

135

140

145

150

that at the instant of opening the ports 172 the valve 148 closes the port 150, thus confining the liquid pressure medium within the cylinder 120 under the piston 118. As the ports 172 are gradually uncovered the liquid medium may flow the faster into the space within the cylinder 120 and thus progressively increase the upward movement of the piston 118. This gradual entrance of the liquid medium under pressure from the cylinder 124 into the cylinder 120 has the effect of securing a smooth and continuous upward movement of the piston 118 and platen 112 and gradual application of pressure to the work interposed between the platens 112 and 102. It is to be understood that the amount of liquid entering the cylinder 120 through the ports 172 is very small indeed. When the piston 118 has practically reached its final upward position the pressure is gradually built up in the cylinder 120 until the full pressure provided for by the press is obtained. The amount of this pressure is regulated through a valve of well-known construction located at 174 (Fig. 5), the amount of such pressure being determined in a well-known manner and indicated by the indicator dial shown at 176. Any tendency to exceed such predetermined pressure results in escape of the liquid from the pipe 126 through the valve 174 and a pipe 178, the upper end of which discharges into the reservoir 144.

When the press is at rest with the piston 118 in its lowermost position, a piece of work may be readily introduced between the upper platen 102 and the work-supporting surface of the lower platen 112. At this time the liquid medium is circulating without interruption, as it is being pumped by the pump 128 through the pipe 126, thence through the port 130 and pipe 142 back to the reservoir 144 from which it again passes by means of a pipe 180 to the pump 128. When the operator is ready to start a pressure-applying operation, he turns the hand wheel 132 in a clockwise direction thereby causing the valve 140 to close the port 130. This immediately cuts off circulation of the liquid medium through the pipe 142 to the reservoir 144 and forces the liquid medium under pressure through pipe 126 into the cylinder 124 through the port 127 at the bottom of the cylinder. The auxiliary piston 122 is caused to rise, at the same time lifting the main piston 118 upwardly in a direction toward the upper platen 102. During the time that the piston 118 is rising, liquid from the reservoir 144 is drawn into the cylinder 120, since the port 150 in the pipe 146 is open at this time. Even if the valve 148 were not depressed by the lever 160, it would be forced downwardly to admit fluid from the reservoir 144 due to the suction effect of the rising piston 118. As the piston 118 and the auxiliary piston 122 are approaching the termination of their upward movement the ports 172 are uncovered and at the same time the port 150 is closed by the valve 148. After the piston has reached substantially its final upward position, pressure is built up in the cylinder 120 to a point determined by the setting of the valve 174, it being obvious, however, that the operator may terminate the application of pressure at a point selected by himself while watching the indicator 176. The pressure for smooth plating or embossing the piece of work between the platens may be continued for any length of time determined by the operator. All the operator must do to terminate the pressure-applying operation is to turn the hand wheel 132 in a counterclockwise

direction, whereby the port 130 is opened, thus permitting the liquid medium to escape through the port 130 and pipe 142 to the reservoir 144. When this happens both the piston 118 and the auxiliary piston 122 move downwardly, due to escape of the pressure medium through the slots 172, and the valve 148 is opened in a positive manner by the piston 118 thereby securing instant release of all pressure since the liquid in the cylinder 120 may then escape through the pipe 146 into the reservoir 144. From one viewpoint, it is the escape of liquid through the ports 172 that initiates return of the large piston toward its initial position of rest. Escape of the liquid from cylinder 120 along the pipe 146 takes place all the time that the piston 118 is descending to its initial position of rest. When the piston 118 and platen 112 have reached their lowermost or work-receiving position, the piece of treated work is removed, and a fresh piece inserted as a preliminary to repetition of the described operations.

Having described my invention, what I claim as new and desire to secure by Letters Patent of the United States is:

1. In a hydraulic mechanism, a piston, an auxiliary piston movable for moving the first-mentioned piston, means for applying pressure to the auxiliary piston to cause movement thereof, means controlled by the auxiliary piston for applying a liquid under pressure directly to the first-mentioned piston, a valve mounted outside of and independently with respect to both pistons, and connecting members between the valve and the first-mentioned piston arranged to operate the valve positively to open position for releasing liquid so that the first-mentioned piston may return toward its initial position.

2. In a hydraulic mechanism, a piston, a cylinder enclosing said piston, an auxiliary piston movable for moving the first-mentioned piston, means for applying pressure to the auxiliary piston to cause movement thereof, means controlled by the auxiliary piston for applying a liquid under pressure directly to the first-mentioned piston, a valve casing mounted rigidly outside of and in parallel relation with respect to said cylinder, a valve in said casing, and a positive mechanical connection between the valve and one of the pistons to cause operation of the valve to effect release of liquid applied under pressure directly to the first-mentioned piston.

3. In a hydraulic mechanism, a piston, an auxiliary piston movable for moving the first-mentioned piston, means for applying liquid under pressure to the auxiliary piston to cause movement thereof, a cylinder enclosing the first-mentioned piston, a cylinder for the auxiliary piston, a port arranged to be alternately opened and closed by the auxiliary piston itself serving as a valve during movement thereof for affording a communication between the two cylinders, whereby pressure is applied directly to the first-mentioned piston by liquid under pressure in the two cylinders; a valve and means connecting the valve to the first mentioned piston to effect release of the liquid, applied under pressure directly to the first-mentioned piston, in timed relation to the movements of said first-mentioned piston.

4. In a press, co-operating platens for applying pressure to opposite surfaces of pieces of work, a piston for moving one of the platens toward the other, an auxiliary piston for moving the first-mentioned piston, means for applying a liquid

- under pressure to the auxiliary piston, a cylinder for the first-mentioned piston, a cylinder for the auxiliary piston, means to apply liquid under pressure to the auxiliary piston the latter piston having a port and passageway arranged to connect the auxiliary piston cylinder with the cylinder for the first-mentioned piston whereby liquid under pressure may pass from the auxiliary piston cylinder to the first-mentioned piston cylinder, means for releasing pressure of the liquid pressure medium on the auxiliary piston so that the auxiliary piston may re-enter its cylinder, thus relieving pressure on the first-mentioned piston, a release valve, and a rod pivotally connected to the first-mentioned piston and arranged to lift the valve upon release of the first-mentioned piston by the auxiliary piston to permit escape of the liquid pressure medium from the first-mentioned cylinder so that its piston may return to initial position.
5. In a press, co-operating platens for applying pressure to opposite surfaces of pieces of work, a piston for moving one of the platens toward the other, an auxiliary piston for moving the first-mentioned piston, means for applying a liquid under pressure to the auxiliary piston, a cylinder for the first-mentioned piston, a cylinder for the auxiliary piston, the latter piston having a port and passageway connecting the auxiliary piston cylinder with the cylinder of the first-mentioned piston whereby liquid under pressure may pass from the auxiliary piston cylinder to the first-mentioned piston cylinder, a manually operable valve for releasing pressure on the auxiliary piston so that the auxiliary piston may re-enter its cylinder, thus relieving pressure on the first-mentioned piston, a valve controlled by the release of pressure upon the auxiliary piston, to relieve pressure on the first-mentioned piston so that it may return to its initial position, and a valve operated mechanically from the first-mentioned piston to open position to facilitate discharge of the pressure medium from the first-mentioned cylinder.
6. In a press, a top platen and a bottom platen, a piston for supporting and moving the bottom platen against the top platen, a cylinder for the piston, an auxiliary piston movable for moving the first-mentioned piston upwardly, a cylinder for the auxiliary piston, the latter piston having a port and passageway for connecting the auxiliary piston cylinder with the cylinder of the first-mentioned piston, means for applying a liquid under pressure to the auxiliary piston, the arrangement being such that at a predetermined point in the upward movement of the auxiliary piston the port is uncovered so that liquid under pressure is applied directly to the first-mentioned piston, means for supplying a liquid pressure medium to the cylinder of the first-mentioned piston, a valve controlled by the first-mentioned piston for retaining the liquid medium under pressure under said piston just as the latter reaches its high point in its pressure applying operation, a second valve for retaining the pressure medium under the first-mentioned piston, and means for simultaneously releasing pressure on the auxiliary piston and on the second valve, whereupon the first-mentioned piston moves downwardly and releases said first-mentioned valve, thus permitting escape of the liquid medium from under the first-mentioned piston whereupon the latter returns to its initial position.
7. In a press, co-operating platens for applying pressure to opposite surfaces of pieces of work, a piston for moving one of the platens toward the other, an auxiliary piston movable for moving the first-mentioned piston, means for applying a liquid under pressure to the auxiliary piston to cause movement thereof, a cylinder for enclosing the first-mentioned piston, a cylinder for the auxiliary piston, said cylinders having a common opening normally filled by the auxiliary piston, a connecting passageway between the two cylinders wholly within the internal walls of the latter and controlled by the movable auxiliary piston for securing application of the liquid pressure medium directly to the first-mentioned piston, and means comprising said connecting passageway arranged to provide for release of pressure in the cylinder of the first-mentioned piston.
8. In a press, co-operating platens for applying pressure to opposite surfaces of pieces of work, a piston for moving one of the platens toward the other, an auxiliary piston movable for moving the first-mentioned piston, means for applying a liquid under pressure to the auxiliary piston to cause movement thereof, a cylinder for enclosing the first-mentioned piston, a cylinder for the auxiliary piston and having wholly within its internal wall both a port and a passageway for connection with the first-mentioned cylinder, the movable auxiliary piston being imperforate and arranged to operate alternately to close and to open the port whereby the liquid pressure medium entering the auxiliary cylinder may pass at a predetermined time into the cylinder of the first-mentioned piston to act directly thereon, and means comprising said port and passageway arranged to provide for release of pressure in the cylinder of the first-mentioned piston.
9. In a press, co-operating platens for treating a piece of work, a piston for moving one of the platens toward the other, an auxiliary piston for moving the first-mentioned piston, means for applying a liquid medium under pressure to the auxiliary piston, a cylinder enclosing the first-mentioned piston, a cylinder for the auxiliary piston, and a lost-motion connection between the two pistons arranged to become operative after the first-mentioned piston and the platen moved thereby meet the resistance offered by the other platen, the auxiliary piston having a port and a passageway arranged to be controlled by the auxiliary piston to permit liquid medium under pressure to pass from the auxiliary piston cylinder to the first-mentioned piston cylinder always at the same point in the movement of the auxiliary piston with respect to said cylinders, whereby liquid medium under pressure is applied directly to the first-mentioned piston at a predetermined point in the upward movement of the auxiliary piston irrespective of the thickness of the work interposed between the two platens.
10. In a press, co-operating platens for treating a piece of work, a piston for moving one of the platens toward the other platen, an auxiliary piston for moving the first-mentioned piston, means for applying a liquid medium under pressure to the auxiliary piston, a cylinder enclosing the first-mentioned piston, a cylinder for the auxiliary piston, a sliding connection between the two pistons arranged to become operative when the first-mentioned piston meets a predetermined resistance offered by the work, and a port arranged to be controlled by the auxiliary piston to permit liquid medium under pressure to pass from the

auxiliary piston cylinder to the first-mentioned piston cylinder always at the same point in the movement of the auxiliary piston with respect to said cylinders irrespective of the thickness of the 5 work.

11. In a press, co-operating platens for treating a piece of work, a piston for moving one of the platens toward the other platen, an auxiliary piston for moving the first-mentioned piston, means 10 for applying pressure to the auxiliary piston, a cylinder enclosing the first-mentioned piston, a port through which a liquid medium under pressure is admitted to said cylinder, the auxiliary piston being arranged to open the port always at 15 the same point in its movement relative to said cylinder irrespective of the thickness of the work, and spring means interposed between the two pistons, said spring means being arranged to support the first mentioned piston and to yield to accommodate work of different thicknesses between the 20 platens.

12. In a press, co-operating platens for treating a piece of work, a piston for moving one platen toward the other, an auxiliary piston for moving the first-mentioned piston, means for applying a liquid medium under pressure to the auxiliary piston, a cylinder enclosing the first-mentioned piston, a cylinder for the auxiliary piston, a spring 25 connected to the auxiliary piston, a plate associated with the spring, and means for adjusting the plate to tension the spring so that the spring will support the first-mentioned piston and yield only when said piston encounters a predetermined resistance, said auxiliary piston having a passageway 30 and a port serving as a communicating passageway between the two cylinders, and the auxiliary piston being arranged to control the port upon yielding of the spring to permit liquid me-

dium under pressure to pass from the auxiliary piston cylinder to the first-mentioned piston cylinder.

13. In a press, co-operating platens for treating a piece of work, a piston for moving one of the platens toward the other, an auxiliary piston for moving the first-mentioned piston, means for applying a liquid medium under pressure to the auxiliary piston, a cylinder enclosing the first-mentioned piston, means for supplying a liquid medium to the cylinder and putting it under pressure comprising a port opening into the cylinder, the auxiliary piston being arranged to control said port always at the same point in the movement of the former relative to said cylinder, and a spring 80 associated with the auxiliary piston, such spring being of such strength and so positioned that the auxiliary piston may move the first-mentioned piston and the platen associated therewith through said spring to work presenting position with respect to the other platen irrespective of the thickness of the work and still control the opening of said port always at the same point in its movement.

14. In a press, co-operating platens for treating a piece of work, a piston for moving one of the platens toward the other, a cylinder enclosing said piston, an auxiliary piston for moving the first-mentioned piston, means arranged to move the auxiliary piston always the same predetermined distance, relative to said cylinder and spring means between the pistons tensioned to support the first-mentioned piston and the platen associated therewith, whereby with a given predetermined stroke of the auxiliary piston pieces of work of different thicknesses may be accommodated due to yielding of said spring means.

PAUL V. J. MERENDA.
